UNITED STATES PATENT OFFICE

136,713

DESIGN FOR A MAGNETO TESTING APPARATUS

Butler J. Haskins, Fox Lake, Ill., assignor to Joseph Weidenhoff, Inc., a corporation of Illinois

Application September 18, 1943, Serial No. 111,159

Term of patent 14 years

To all whom it may concern:

Be it known that I, Butler J. Haskins, a citizen of the United States, residing at Fox Lake, in the county of Lake and State of Illinois, have invented a new, original and ornamental Design for a Magneto Testing Apparatus, of which the following is a specification, reference being had to the accompanying drawings, forming a part thereof, in which:

Figure 1 is a front elevation of a magneto testing apparatus showing my new design;

Figure 2 is a side elevational view of the same device;

Figure 3 is a perspective view of the device; and Figure 4 is a plan view thereof.

I claim:

The ornamental design for magneto testing apparatus, as shown.

BUTLER J. HASKINS.
